COLLAPSIBLE AWNING

Frederick E. Nelson, Greentree, Pa.

Application January 26, 1951, Serial No. 207,876

1 Claim. (Cl. 160—132)

1

This invention relates generally to collapsible awnings and more particularly to a collapsible awning made up of rigid sections that telescope into one another when closed.

Collapsible awnings made of sheet metal are well known in the art. However, their structures are expensive to manufacture and are not conducive to good appearance as the sections do not have adequate clearance and they slide and scrape on one another removing the paint and causing deep and ugly scratches on the broad faces of the sections. If additional clearance was provided in such prior art structures, they could not perform as intended by their disclosures. They would be too flimsy and flexible to properly operate. Even though the gauge of the metal would be relatively heavy and the edges bound with beads or turned in flanges their structures are bound to flex and cause one part to scrape against another resulting in disfigured unsightly awnings. When made of sheet steel the scratched places soon rust making it necessary to remove and repaint or discard the awnings entirely.

Another disadvantage of the closely spaced sections of the present collapsible awnings is that it prevents air from freely circulating through the awning.

The principal object of this invention is the provision of an improved collapsible metal awning structure that is simple in construction making it economical to reproduce. The awning comprising this invention may be constructed of light gauge aluminum panels cut from relatively narrow stock and fabricated with some heavier parts to provide a rigid structure which results in an inexpensive awning. Each of the collapsible sections of the awning is made of three panels, two sides and a top. All of the side panels for each section may be cut with the same dies although the sections are progressively smaller. The same is true of the top panels. This feature materially aids in maintaining a low initial cost of this collapsible awning.

A continuously outwardly extending marginal flange along the front edge of each panel and a right angle corner plate is used to connect the flanges on adjacent top and side panels to form a rigid frame for each section of the awning.

The joint between the ends of the top panel and the side panels has a bearing plate fastened therein. One edge of these bearing plates is continuous and extends beyond the outer face of the section. This continuous edge functions

5 on a guide bar that may engage and rub against a portion of the next larger section of the awning. This guide bar keeps the adjacent panel surfaces from becoming scratched.

The right angle corner plates and the bearing plates at each corner of each section are preferably made of heavy stock and in combination with the marginal flange they make a rigid section out of very light gauge panels.

10 Other objects and advantages appear in the following description and claim.

The accompanying drawing shows, for the purpose of exemplification without limiting the invention or claim thereto, certain practical embodiments of the invention wherein:

Fig. 1 is a perspective view with the awning partially extended;

Fig. 2 is a view in front elevation showing the awning collapsed;

Fig. 3 is an isometric view of one section of the awning;

Fig. 4 is an enlarged view of the fabricated corner of a section with parts broken away;

Fig. 5 is an enlarged view of the upper part of a side panel of an awning section;

Fig. 6 is an enlarged view of the bearing plate shown in Fig. 4;

Fig. 7 is an enlarged view of the right angle corner plate;

Fig. 8 is an enlarged view looking under the corner shown in Fig. 4;

Fig. 9 is a perspective view of the anchor member for mounting the awning;

Fig. 10 is a sectional view of a modified form of bearing plate;

Fig. 11 is a sectional view of a modified form of bearing plate;

Fig. 12 is a sectional view of a modified form of bearing plate.

40 Referring to Figs. 1 to 9, inclusive, of the drawings it will be noted that the collapsible awning 1 is made up of a series of sections, each section being capable of telescoping within the next larger section to fully collapse the awning as shown in Fig. 2.

45 As disclosed in Fig. 9 the anchor member 2, which supports the awning on the face of the building, is constructed from two angle members 3 and 4 that are joined at their upper end by the cross panel 5. The cross panel 5 is provided with an outwardly extending flange 6 that matches the outwardly extending flanges 1 of the angles 3 and 4. The lower edge of the panel is also provided with a downwardly and outwardly disposed flange 8. The flanges of the angles 3

and 4 that lie in a common plane are provided with the bayonet slots 10 enabling the awning to be readily inserted over lugs secured to the face of the building. This type of construction permits the awning to be readily removable without defacing or otherwise removing parts from the surface of the building itself. The last or largest sections 11 of the awning are riveted or otherwise secured to the outwardly projecting flanges 7 of the angles 3 and 4 and to the outwardly projecting flange 6 of the cross panel 5.

Each of the multiple sections 12 of the collapsible awning, as shown in Figs. 1 and 2, is illustrated in Fig. 3 and comprises a top panel member 13 and the side panel members 14 and 15. Each side panel, as shown in Fig. 5, is provided with an inturned flange 16 at the upper end thereof and an outwardly extending marginal flange 17 along the face thereof. The side panel 15 has the same flanges although the top flange is turned inwardly under the top panel 13.

As shown in Figs. 4 to 8 the inwardly projecting flange 16 of the side panel 14 is riveted or otherwise secured to the top panel 13 by the rivets 18. However, the bearing plate 20 is secured intermediate of the flange 16 and the under face of the end of the panel 13. The rivets 18 secure the end of the top panel 13 and the top of the side panel together and with the bearing plate interposed therebetween.

The outer side edge of the bearing plate 20 is provided with a continuous marginal guide bar 21 and the rear of the bearing plate 20 is provided with an upwardly and forwardly projecting hook or extension 22. The bearing plate, as shown in Fig. 6, is the same for each end of each top panel member 13, and the continuous guide bar 21 may be either side of the plate 20 depending upon which side of the section the plate is mounted.

Each top panel 13 is provided with an upwardly extending flange 23 that has a rearwardly extending portion 24. Thus, the outwardly projecting flange 23 of the top panel 13 and the upwardly projecting flanges 17 of the side panels 14 and 15 provide a rigid frame when secured at their adjacent ends by the right angle corner plates 25 which is shown in Fig. 7. The right angle corner plates 25 match the outer edge of the flanges 17 and 23. However, their inner edges 26 and 27 extend beyond the inner face of the panels 13, 14 and 15. This inwardly projecting edge of the right angle corner plates 25 provides a bearing surface that may be engaged by the guide bar surface 21 of the next smaller section 12 of the awning. If the right angle corner plate 25 is mounted, as shown in Fig. 7, the inwardly projecting edge 27 will engage the guide bar 21, but the inner projecting edge 26 will be engaged by the outwardly extending hook members 22 of the next smaller section thereby providing a stop to limit the outwardly telescoping action of the sections.

The plate 20 and the right angle corner plate 25 are preferably made of a heavier gauge than the light aluminum gauge from which the panels 13, 14 and 15 are constructed. By making these plates of heavier gauge each frame is made stronger and rigid which could not be obtained if a piece of light material of the same gauge were employed. Again I wish to point out that this gauge provides a better bearing engaging surface than the light gauge aluminum.

As shown in Fig. 2 each of the flanges 17 on the side panels 14 and 15 mask the space between

the adjacent sections when the collapsible awning is closed. Likewise the upwardly projecting flange 23 of the top panels 13 masks and closes the ventilating space between the top panels of each of the sections.

The rearwardly extending flanges 24 on the top of the outwardly extending flanges 23 of the top panels 13, engage the face of the right angle corner plates 25 of the next larger section. Thus, we have a line engagement produced only by the rear edge of the flange 24 which prevents the structure from being marred, as the heavy right angle corner plates will receive the engagement of the rear edge of the aluminum flange 24. A rubber cushion not shown may be employed as a stop between these members. Thus, the flange 24, which is a portion of the rigid frame made up by the flanges 17 and 23, provides a stop to limit the extent of the inward telescoping action of the collapsible awning.

The lower end of the side panels 14 and 15 of each of the sections are rounded and provided with a concentric opening as illustrated at 28. The largest section 11, as shown in Fig. 1, provides the bearing for receiving the bolt 30 on which each of the sections are pivoted. The bolt 30 extends through the openings 28 in each of the sections and the hole 28 may be formed by pressing the stock of the opening into a washer of material thickness and thus hold the washer tightly to the side panel on the inner surface thereof. The thickness of these washers is equivalent to the spacing required between the adjacent panel members. The spacing is such that the guide plates do not have to engage the corner plates unless the panels are twisted or moved laterally. In this way the washer not only functions to maintain the proper spacing at the lower end of the panels, but also provides an increased bearing surface for each of the sections of the collapsible awning.

This collapsible awning may be raised and lowered by means of a rope 34 attached to the smallest and innermost section, which rope would be drawn upwardly to the frame where it may be looped through plastic rings such as indicated at 31 and 32 and then drawn down and secured to the fastening means as indicated at 33 on the panel 15 of the innermost or smallest section as shown in Fig. 2. Thus by unlatching the rope from the fastening means 33 the awning may be drawn up in its collapsed position, as shown in Fig. 2, and tied in place or it may be loosened and permitted to open to any extent desired in view of the fact that the rope is only attached to the smallest and innermost section. This section must, of course, be raised to pick up each section in turn when collapsing the awning.

Modification of the guide bar is shown in Figures 10, 11 and 12 wherein the plates employed in forming the joint between the side panels 14 and the top panels 13 may be constructed to hold the outer end of the latter bent over as shown at 37 in Fig. 10. The guide bar plate 38 carries the outward extension 22, and also extends laterally beyond the end of the top panel 13 and then downwardly around the bottom edge 37, as shown at 39, and is returned over the top edge of the panel 14 as indicated at 40. The inwardly projecting flange 16 has been eliminated from the top of the panel 14. The guide bar 41 is formed and it may operate against the inner surface 42 of the next larger plate.

A similar structure is shown in Fig. 11 wherein the plate 43 extends outwardly and downwardly

to form the guide bar 44 and then folds up over the end 37 and the top of the panel 14 and downwardly to provide the inner surface 45, the only difference between the structures of Figs. 10 and 11 being the position of the guide bar relative to the panel 13.

A similar structure is shown in Fig. 12 wherein the guide bar is formed at 46 from the plate member that is riveted to the under side of the panel 13 and is likewise riveted to the inside of the side panel 14 to provide the bearing surface 47. This structure is quite similar to the plate 20, but eliminates the flange 16 of the panels 14 and 15. The use of the guide bars such as shown at 41, 44 and 46 against their respective surfaces 42, 45 and 47 would eliminate the use of the inner extensions 27 on the right angle corner plates 25.

When this collapsible awning is made up of light gauge aluminum with the heavier plates at the corners, which have the outwardly projecting flange between the side and top panels, the structure is still very light but very strong in view of the fact that these plates are not large even though made from a heavier gauge, yet they provide a materially stiffer section than could be obtained otherwise.

I claim:

A collapsible awning comprising a series of inverted U-shaped sections nested in telescopic relation and pivotally mounted in spaced relation to each other to allow for ventilation therebetween, each awning section having a top and two side panels, an inturned flange at the upper end of each side panel, a flat stiffening bearing plate fastened between each inturned flange and the end of its corresponding top panel, an outwardly extending marginal flange along the front edge of each side and top panel, a flat stiffening right angle corner plate connecting the adjacent ends 40 of the outwardly extending flanges of each side and top panel of each awning section, said out-

wardly extending marginal flanges and said stiffening right angle corner plates defining a continuous rigid frame on the face of each awning section to stiffen the same, the rigid frame of 5 each consecutive awning section overlapping a portion of the frame of the next adjacent larger awning section to mask the ventilating space between the corresponding panels of the next adjacent larger awning section when the awning sections are telescoped, a rearward extension on 10 the marginal flange of each top panel to engage a portion of the marginal flange of the next larger awning section when the awning is collapsed in telescopic relation to space the awning sections from each other, said flat stiffening right angle corner plates each having a horizontal and 15 a vertical projection inwardly of the top and side panels respectively, a rearward extension on each of said flat stiffening bearing plates to engage the horizontal inward projection of said flat stiffening right angle corner plates of the next adjacent larger awning section to limit the outward telescopic movement of each awning section, and a lateral continuous portion on each of said 20 flat stiffening bearing plates to engage the vertical inward projection of the flat stiffening right angle corner plate of the next adjacent larger awning section and prevent their panel faces from scraping one another.
